Des. 223,666

Patented May 23, 1972

223,666

COATING HOLIDAY DETECTOR

Charles W. Eisele, Warminster, Pa., assignor to
H. C. Price Co., Bartlesville, Okla.

Filed Feb. 25, 1971, Ser. No. 119,068

Term of patent 14 years

Int. Cl. D10—05

U.S. Cl. D26—1

Fig. 1.

Fig. 2.

FIG. 1 is a side elevational view of a coating holiday detector showing my new design;

FIG. 2 is a side elevational view thereof showing the side opposite that shown in FIG. 1;

FIG. 3 is a top plan view thereof;

FIG. 4 is a front elevational view thereof;

FIG. 5 is a bottom plan view thereof; and

FIG. 6 is a rear elevational view thereof.

I claim:

The ornamental design for a coating holiday detector, as shown.
